SPONGE RACK

Emory L. Groff, Pompano Beach, Fla., assignor to Emory L. Groff, Jr., Bethesda, Md.

Original design application Jan. 28, 1965, Ser. No. 83,619, now Patent No. 203,058, dated Nov. 30, 1965. Divided and this application Oct. 21, 1965, Ser. No. 456

Term of patent 14 years

(Cl. D44—29)

FIG. 1.

FIG. 2.

FIG. 3.

FIG. 4.

FIG. 1 is a perspective view of a sponge rack showing my new design;

FIG. 2 is a top plan view of the sponge rack shown in FIG. 1;

FIG. 3 is a side elevation thereof; and

FIG. 4 is an end view thereof.

This is a division of application Serial No. D.83,619 of January 28, 1965, now Design Patent D.203,058 of November 30, 1965.

I claim:

The ornamental design for a sponge rack, substantially as shown and described.
